UNITED STATES PATENT OFFICE.

SALVATORE SCOGNAMILLO, OF NEW YORK, N. Y.

SIGNAL-HORN.

1,140,290.

Specification of Letters Patent.

Patented May 18, 1915.

Application filed September 5, 1913. Serial No. 788,336.

To all whom it may concern:

Be it known that I, SALVATORE SCOGNAMILLO, a citizen of the United States, residing at New York city, in the county of New York and State of New York, have invented new and useful Improvements in Signal-Horns, of which the following is a specification.

My present invention relates to improvements in warning signals and more especially to those adapted for use upon automobiles embodying a vibratory diaphragm or sound-producing medium and a revoluble toothed wheel and electric motor for vibrating the diaphragm.

The primary objects of the invention are to provide an improved operating tooth or projection for the diaphragm whereby a motor of relatively large size and power can be accommodated within a relatively small casing, and to provide an improved arrangement for the mounting of the actuating motor.

To these and other ends, the invention consists in certain improvements, and combinations and arrangements of parts, all as will be hereinafter more fully described, the novel features being pointed out particularly in the claims at the end of the specification.

In the accompanying drawing:—Figure 1 represents a longitudinal section through a signal horn embodying the present invention; Fig. 2 represents a section on the line 2—2 of Fig. 1; Fig. 3 is a perspective view of a portion of the field magnet of the motor and the supporting arm therefor.

Similar parts are designated by the same reference characters in the several views.

The present invention is applicable in general to electric horns or warning signals of different constructions, that shown in the accompanying drawing representing an example. In this instance, 1 designates the flexible vibratory diaphragm which is clamped at its periphery between the flange 2 of a bell or projector 3 and a ring 4, screws or bolts 5 serving to draw the parts together and to retain them in such relation. A cup-shaped cover or casing 6 is provided which serves to inclose the motor and to

protect the same from dust or injury, this casing or cover being removable to permit access to the motor. The forward edge of the removable cover or casing has a sliding fit upon a flange 7 which projects rearwardly from the ring 4 and it may be secured in position by screws, as shown.

In the usual construction of electric horns of this type, the vibratory sound-producing diaphragm is vibrated mechanically by a toothed wheel driven by an electric motor and acting upon a tooth or projection attached to the diaphragm. In order to accommodate a relatively large and strong motor within the relatively small space available within the casing the motor, according to the present invention, is mounted in substantially the center of the casing and is supported by a pair of lugs 8 which project rearwardly at diametrically opposite points from the ring 4. The motor has a field 9 which is preferably laminated or built up of a number of punched plates which are riveted or otherwise secured together, this laminated construction providing a field of the maximum magnetic strength and efficiency. The two outer plates of the field are formed with outwardly projecting flanges 10, the lugs 8 on the ring 4 fitting against opposite sides of the field and between these flanges 10, thereby insuring a correct position of the motor relatively to the diaphragm, and screws 11 are tapped into the field of the motor and extend through slots 12 formed in the lugs 8, these screws being movable longitudinally in the slots and thereby affording an adjustment for the motor in a direction toward or from the diaphragm, thereby enabling the character of the sound produced by the diaphragm to be varied as desired. The motor field is energized as usual by a coil 13. The motor is provided with an armature 14 which is revoluble between the field poles, and the armature and field of the motor receive current from any suitable source through the wires 15. In the present instance, the toothed wheel 16 which serves to mechanically vibrate the diaphragm is fixed on the armature shaft of the motor at one side of the field thereof. As the motor

is located in substantially the center of the casing this toothed wheel occupies a position toward one side of the casing. In order to obtain the proper acoustic results from the diaphragm, the projection or tooth which coöperates with the toothed wheel on the armature shaft to vibrate the diaphragm must be secured to the center of the diaphragm. The present invention provides a novel construction of tooth or projection, it comprising a body 17 which is secured to the center of the diaphragm by a rivet 18 or other suitable means and has a radial or laterally extending arm 19 which is spaced from or out of contact with the adjacent face of the diaphragm, the extremity of this arm being directed rearwardly and forming a tooth 20 to be engaged by the ratchet-shaped teeth of the toothed wheel 16. Rotation of the motor armature and consequently the toothed wheel 16 connected thereto produces rapid vibration of the diaphragm through the medium of the tooth or projection described, and the construction of the projection is such that the strength or quality of the tone produced by vibration of the diaphragm is not impaired nor is the vibration of the diaphragm hampered. The present invention enables a relatively large and strong motor to be used within a comparatively small casing, thereby insuring greater certainty in the operation of the device as a warning signal.

A novel and advantageous feature of the present invention is that the toothed actuating wheel for the diaphragm can be so set that when the motor is not energized by the electric current the teeth of the toothed wheel only engage lightly or are just clear of the projection or tooth on the diaphragm, thereby enabling the motor to start revolving easily or freely when the current is supplied thereto, thus insuring certainty in the operation of the signal. When the current is supplied to the motor, the field magnets thereof, owing to their close proximity to the diaphragm and the projection 19, will attract the center of the diaphragm toward them, the diaphragm being composed of magnetic metal, and this attraction of the diaphragm brings the actuating projection thereon into operative engagement with the revolving toothed wheel, the strength of the sound produced increasing with the degree of attraction. This arrangement also gives a louder sound as the magnetic attraction of the diaphragm by the field magnets of the motor returns the diaphragm more quickly after each deflection by the toothed wheel, thereby amplifying the range of vibration of the diaphragm.

I claim as my invention:—

1. In a signal of the class described, a vi-

bratory sound-producing diaphragm, an actuating projection secured at one point to 65 the diaphragm and having an arm extending toward the periphery of the diaphragm and out of contact with the adjacent face thereof, and an electric motor having a revoluble toothed wheel coöperative with said 70 actuating projection and having field pieces located at opposite sides of said projection.

2. In a device of the class described, a vibratory sound-producing diaphragm, an actuating projection secured to the center of 75 the diaphragm and having an arm extending radially in a direction parallel to the plane of the diaphragm but out of contact with the face thereof, the outer extremity of said projection being formed with an operating tooth, and an electric motor having 80 a revoluble toothed wheel coöperative with said actuating tooth and having its field pieces straddling said projection.

3. In a signal of the class described, the 85 combination with a motor having field pieces, an armature and a toothed wheel revoluble therewith, a vibratory sound-producing diaphragm located opposite to the poles 90 of the motor field pieces, and an actuating projection secured to the center of the diaphragm at a point between the poles of the motor field pieces and having an arm extending radially of the diaphragm and out 95 of contact with the face thereof, the outer end of said projection coöperating with said toothed wheel.

4. In a signal of the class described, the combination with a vibratory sound-producing diaphragm, a member having a pair of 100 lugs extending in parallelism therefrom, a motor having an armature provided with a toothed wheel to operate the diaphragm and having a field provided at opposite sides with pairs of flanges to slidably engage said 105 lugs to position the motor relatively to the diaphragm.

5. In a signal of the class described, the combination with a vibratory sound-producing diaphragm, a member having a pair of 110 lugs extending in parallelism therefrom, a motor having an armature provided with a toothed wheel to operate the diaphragm and having a field composed of assembled plates, the outer plates formed with flanges adapted to coöperate with said lugs to position the motor and permit adjustment thereof in a direction toward or from the diaphragm. 115

6. In a signal of the class described, the combination of a vibratory diaphragm, and 120 an electric motor provided with a toothed wheel for vibrating the diaphragm and having a field operative to attract the diaphragm toward the toothed wheel.

7. In a signal of the class described, the 125 combination of a vibratory diaphragm hav-

ing an actuating projection, an electric motor, and a toothed wheel opposite to the projection on the diaphragm and operative by the motor, energization of the motor attracting the diaphragm and moving the actuating projection thereon toward the toothed wheel.

In testimony whereof I have hereunto set my hand in presence of two subscribing witnesses.

SALVATORE SCOGNAMILLO.
